[57] CLAIM

The ornamental design for a bubbling bath foot pad, as shown and described.

DESCRIPTION

FIG. 1 is a top plan view of a bubbling bath foot pad, showing our new design;

FIG. 2 is a left side elevational view thereof;

FIG. 3 is a right side elevational view thereof;

FIG. 4 is an end elevational view thereof;

FIG. 5 is an end elevational view thereof, opposite that shown in FIG. 4;

FIG. 6 is a bottom plan view thereof; and

FIG. 7 is a side elevational view thereof on a reduced scale, the broken line showing of the bathtub and fixtures is for illustrative purposes only and forms no part of the claimed design.

FIG. 3

FIG. 5

FIG. 1

FIG. 4

FIG. 2

FIG. 6

FIG. 7
